JET MOTOR

Kenneth Wright, Flint, Mich.

Application November 27, 1950, Serial No. 197,747

23 Claims. (Cl. 60—35.6)

1

The present invention relates to a motor and more particularly to a jet type motor comprising a plurality of combustion chambers.

It is an object of the present invention to provide a jet motor having a plurality of combustion chambers in which variations of pressure within one chamber are effective to control the operation of another chamber.

It is a further object of the present invention to provide a jet type motor having a plurality of combustion chambers in which the pressure developed within one chamber during combustion of a charge of fuel therein supplies the power for actuating the means for supplying air and fuel to another chamber.

It is a further object of the present invention to provide a jet type motor employing a constantly effective or operative ignition means and for controlling the sequence of charging and igniting the charge in the chamber by timed operation of air inlet means and fuel injector means.

It is a further object of the present invention to provide a pulsating jet type motor.

It is a further object of the present invention to provide a pulsating jet type motor comprising a plurality of combustion chambers and timing means for controlling the several chambers.

It is a further object of the present invention to provide a jet type motor of the type described in the preceding paragraph in which variation of pressure in one chamber is effective to control the charging and ignition of the charge in a second chamber.

It is a further object of the present invention to provide a jet type motor having a combustion chamber, a fuel injector, an air inlet valve, and an air control valve with a single manually operated member effective to adjust fuel and air supply simultaneously.

Other objects and features of the invention will become apparent as the description proceeds, especially when taken in conjunction with the accompanying drawings, wherein:

Figure 1 is a rear elevation of a motor of the character described with parts omitted for clarity.

Figure 2 is a plan view of the motor shown in Figure 1.

Figure 3 is a side elevational view of the motor shown in Figure 1 with parts broken away.

Figure 4 is a fragmentary side elevation, partly in section, on the line 4—4, Figure 1.

Figure 5 is an enlarged section on the line 5—5, Figure 4.

Figure 6 is a section on the line 6—6, Figure 1, 55

2

Figure 7 is a diagrammatic view illustrating a motor comprising three associated combustion chambers.

Figure 8 is a fragmentary diagrammatic view illustrating a simple lost motion connection for the fuel pump.

Referring now to the drawings the motor comprises a pair of combustion chambers 10 and 12, each of which is illustrated comprises an upper cylindrical portion 14 and an elongated conical portion 16. At the lower end of the conical portion 16 there is a restricted exhaust 18. The two exhausts 18 are brought together and are continued to constitute a jet pipe 20 including a partition 22 which separates the products of combustion from each of the combustion chambers. As best seen in Figure 4, each of the combustion chambers is provided with a head 24 having a plurality of circumferentially spaced air passages 26 and a central part 28 including an upwardly extending sleeve 30 having a cylindrical bore 32 therethrough for the reception of a valve stem later to be described. The head 24 is illustrated in Figure 1 as bolted to the upper end of the combustion chamber by a plurality of bolts 34 extending into threaded ears 36 which are provided on the upper end of the combustion chambers. The head 24 is shaped to provide a circular valve seat 38 and associated with the valve seat 38 is a valve 40 including a valve stem 42 extending upwardly through the cylindrical bore 32.

Each of the combustion chambers is provided with ignition means which are constantly or immediately effective to ignite fuel charges as introduced into the chamber. For this purpose a constant glow spark plug such as indicated at 44, may be employed.

Each of the combustion chambers is provided with fuel injection means including an injection nozzle 46 which preferably is located adjacent the upper end of the chamber and directly opposite to the ignition means 44. As best seen in Figure 4, the fuel injection means comprises a plunger type injector 50 including a cylinder 53 and a solid vertically movable piston 60. Adjacent the lower end of the cylinder 53 is a fuel inlet 62 and at its lower end is an outlet indicated generally at 64. A fuel conduit 66 extends from the outlet 64 to the injection nozzle 46.

In practice the motor operates at a high rate of speed and consequently it has been found desirable to employ a special type of valve for controlling the fuel inlet to the pump and the fuel outlet from the pump. The valve is illustrated in Figure 5 as comprising a flat lightweight disc

68 which is smooth on one side and which on its opposite side is provided with grooves 70. The valve disc 68, as best seen in Figure 4, operates in a restricted chamber against opposed flat surfaces provided by the fittings 72 and 74. Thus, on the down stroke of the piston 60 the valve 68 is forced against the flat surface of the fitting 74 but a passage for fuel is provided through the grooves 70 to the fuel outlet 10 passage 76 formed in the fitting 74. On the other hand, when the piston 60 moves upwardly the valve disc 68 is drawn upwardly against the flat under surface of the fitting 72. Since the upper surface of the disc 68 is smooth and flat it closes the passage 76 provided in the fitting 72. A similar arrangement is provided for the fuel inlet except that the valve disc is of course reversed to permit flow of fuel into the cylinder 58 on the upstroke of the piston 60.

The motor is constructed and arranged such that variations in pressure in one of the combustion chambers controls and operates means for admitting air and fuel to the other chamber. For this purpose both the fuel injector 50 and the air inlet valve 40 are operated by a lever 80 which in turn is rocked about its pivot axis by a pressure responsive actuator such as the piston and cylinder device 82. The lever 80 for each of the combustion chambers 10 and 12, is mounted on a longitudinally extending shaft 84 which as best seen in Figure 2, is supported at its ends by a pair of plates 86 one of which is suitably secured to the head 24 of each of the combustion chambers. The valve 40 is provided with a spring 88 biasing the valve towards its upper closed position. For this purpose the spring surrounds the sleeve 32 and at its upper end engages a spring seat 90 pinned or otherwise secured to the valve stem 42. The lever 80 includes an enlarged end portion 92 which is internally threaded and receives an adjusting screw 94 having a rounded lower portion engageable with the upper free end of the valve stem 42. The screw 94 is retained in adjusted position by a locking nut 96.

The opposite end of the lever 80 is connected by a pin 98 to the upper end of a piston rod 102 carrying at its lower end a piston 104 vertically movable in the cylinder 104 of the piston and cylinder device 82. The lower end of the cylinder 104 is provided with a coupling 106 which connects the cylinder to a conduit 108. As best seen in Figure 1, the conduit 108 connects the piston and cylinder device 82 of the combustion chamber 12 to the combustion chamber 10. In like manner, the piston and cylinder device associated with the combustion chamber 10 is connected by a conduit 110 to the combustion chamber 12.

To control the flow of air into the combustion chambers each of the heads 24 is provided with an air control valve plate 112. The plates 112, as best seen in Figure 2, are each provided with ports 114 shaped to conform generally to the openings provided in the upper surface of the heads 24 by the passages 26. The air control valve plates 112 are recessed in grooves 116 formed in the upper surface of the heads 24 and are provided with central openings 118 engaging the central part 28 of the heads 24. The valve plates 112 are retained down against the upper surface of the head 24 by a washer 120 received beneath the lower end of the spring 88 so that the spring presses the plate 112 firmly against the upper surface of the head 24.

Means are provided for effecting vertical reciprocation of the plunger or piston 60 of the fuel injector 50. This means comprises a connecting rod 122 which is provided with a pivot connection 124 at its lower end with the piston 60. The upper end of the connecting rod 122 carries a pivot pin 126 by which it is connected to a block 128 slideable in an elongated slot 130 provided in the lever 80. Means later to be described are provided for adjusting the block 128 longitudinal of the slot 130 and as will be readily apparent this changes the length of the stroke of the plunger or piston 60 and hence provide means for controlling the amount of fuel injected into the combustion chamber upon each oscillation of the lever 80.

It is desirable to effect correlated changes in the amount of air supplied to the cylinder and the amount of fuel. Accordingly, a single manual control means is provided for effecting simultaneous adjustment of the block 128 in the slot 130 and rotation of the air control valve plate 112. This means comprises a manual control lever 132 carried by a bracket 134. The lever 132 is mounted for rocking movement about a pivot support 136 and is connected by a link 138 to a lever 140 which is secured to a control shaft 142 so that rocking of the lever 140 by the manual control 132 results in rocking the shaft 142. Secured directly to opposite sides of the lever 140 are a pair of ball elements 144 and to each of these is connected a link 146 as best seen in Figure 2, which at its other end is connected to a similar ball element 148 extending upwardly from the air control valve plate 112. The shaft 142 also is provided with two downwardly extending injector control arms 150 each of which at its lower end is provided with an arcuate slot 152 which receives the projecting ends of the pivot pins 126 connecting the connecting rods 122 to the blocks 128.

Accordingly, as the operator moves the manual control lever 132, the lever 140 is rocked about the axis of shaft 142, thus effecting simultaneous rotation of the air control valve plates 112. At the same time the shaft 142 is rotated and the two fuel injector control arms 150 are moved therewith effecting simultaneous correlated movement of the blocks 128 longitudinally of the elongated slots 130. This last has the effect of changing the length of stroke of the plunger 60 and the parts are proportioned and designed such that the air flow into the chamber is automatically correlated with the amount of fuel injected therein.

The operation of the pulsating type multiple chamber jet motor is probably apparent from the foregoing description of the device but will be briefly reviewed in the interest of clarity. In order to start the motor the ignition means are energized and one or the other of the levers 80 is depressed to the full extent thus opening air inlet valve 40 and compressing spring 88. At the same time the fuel injector plunger 60 is drawn upwardly thus drawing fuel into the cylinder 58 beneath the plunger 60. Thereafter, the operator releases the lever 80. The spring 88 rocks the lever in a counterclockwise direction as seen in Figure 4, thus closing the air inlet 40 and injecting a charge of fuel through the nozzle 46 into the combustion chamber. Ignition of the fuel in the combustion chamber by the constantly effective ignition means produces a high pressure within the chamber. Products of combustion are expelled through the restricted jet nozzle or outlet

with a high velocity and thus establishing the thrust. At the same time pressure from the combustion chamber first ignited by the foregoing is communicated to the piston and cylinder device 82 of the next chamber to operate. This pressure moves the piston 102 upwardly, rocking its lever 80 in a direction to compress the spring and open the air inlet valve and to operate the plunger of the fuel injector on a suction stroke. As soon as the pressure falls in the chamber first fired, the spring 88 causes the lever to rock in the opposite direction thus moving the piston 102 downwardly in the chamber 104 and at the same time operating the fuel injecting plunger on its feeding stroke.

In the case of a two chamber motor, as illustrated in the figures, the two chambers are charged and fired alternately, variations in pressure of one controlling and actually operating the fuel and air supply means of the other.

Inasmuch as the jet exhaust from each of the chambers is brought into a common jet exhaust nozzle or pipe 20, the flow of products of combustion out of one-half of the jet induces a flow through the other chamber when its air inlet valve 40 is opened.

While a two chamber motor is illustrated it will of course be apparent that if desired the same principle could be applied to a motor having three or more chambers which could be fired in sequence. Thus, in the event three chambers were provided, each would have a piston and cylinder control device connected to one of the other chambers so that firing of any one chamber will bring about firing of the chamber whose piston and cylinder control device is connected to the first chamber after the pressure has fallen in the chamber first fired. In Figure 7 such an arrangement is diagrammatically illustrated. In this figure three associated combustion chambers A, B, and C, are provided each having a discharge conduit connected to a single jet exhaust 20a. Each of the chambers has a fuel pump 50a connected to a fuel nozzle (not shown) by a conduit 66a. Each of the chambers includes an air inlet valve of the type previously described including a valve stem 62a adapted to be urged toward closed position by a spring of the type illustrated in Figure 3, and adapted to be forced toward open position by a lever 80a pivoted intermediate its ends by a pivot 84a. Suitable connection is provided between the lever 80a and each of the fuel pumps 50a. A pressure responsive device such for example as a piston and cylinder indicated at 62a is connected to each of the chambers by a conduit 108a. It will be observed in Figure 7 that the piston and cylinder actuating the fuel pump and air inlet valve of the chamber A is connected to the combustion chamber C. In like manner, the piston and cylinder actuating the fuel injector and air inlet valve of the chamber C is connected to the chamber B. The fuel pump and air inlet valve of chamber B are connected to the piston and cylinder device connected to chamber A. Accordingly, when chamber A fires the air inlet valve of chamber B is opened, and when the pressure in chamber A falls, the air inlet valve of chamber B closes and fuel is injected therein. The resulting combustion of the charge in chamber B opens the air inlet valve of chamber C and as pressure falls in chamber B, the air inlet valve of chamber C closes and its fuel injector operates. Combustion of the charge in chamber C results in opening of the air inlet valve of chamber A, and as pressure falls in chamber B

the air inlet valve of chamber A closes and its fuel injector operates. Accordingly, the three combustion chambers A, B, C will sequentially fire in the order A-B-C.

5 While the fuel injector plunger 60 is illustrated as connected positively to the lever 80 for movement therewith, it will be appreciated that if desired suitable lost motion connections may be provided so that the feeding stroke of the plunger 10 60 may take place only during a predetermined portion of the return movement of the lever 80, thus timing the injection of fuel with respect to the closure of the air inlet valve 40.

In Figure 8 there is diagrammatically illustrated 15 a suitable lost motion connection for the fuel pump. In this case the connecting rod 122a may be provided with an elongated slot 123a which receives a pin 124a carried by the upper end of the piston rod 60a. In this case it will 20 be observed that a lost motion is provided which will require substantial rocking movement of the lever 80 in either direction before the piston is moved. The provision of the lost motion connection of course shortens the stroke of the piston, 25 but this can be compensated for by adjusting pin 126 to the proper position in the slot 130 (Figure 4).

If desired, each of the combustion chambers 30 10 and 12 may be provided with suitable cooling means, such for example as radiating fins or water jackets, or the like. However, since this involves only conventional cooling principles, the cooling structure is not illustrated herein.

The present motor is particularly desirable in 35 marine propulsion and is especially suitable for an outboard motor. Accordingly, in Figure 3 there is illustrated a bracket 130 by means of which the entire motor may be mounted on the stern of a boat and a clamping screw 162 is illustrated for cooperation therewith. A rudder of conventional construction may be supported by the jet exhaust pipe and the entire motor assembly may be rotatable in a bushing 164, a tiller 166 being illustrated for effective steering thereby. The motor support 160 is provided with a pivot 40 connection 168 to the bushing 164 so that the jet exhaust pipe and rudder may be elevated by tilting the motor as a unit.

In the illustrated embodiment of the invention 50 the chambers are shown as vertically disposed. In this case of course it will be appreciated that the jet exhaust pipe is turned to occupy a generally horizontal plane so that its thrust will be horizontal with the motor mounted as shown in the figures. However, the motor need not be disposed with its chambers extending vertically and if desired, the chambers may be disposed so that products of combustion escape from the chambers and thence through the jet exhaust pipe in substantially straight line relationship.

55 The present motor is characterized particularly by its simplicity and efficiency. The number of operating parts are kept to a minimum and the entire motor may be constructed of relatively light material so that its overall weight is substantially less than a conventional outboard motor of comparable power.

The drawings and the foregoing specification 60 constitute a description of the improved jet motor in such full, clear, concise and exact terms as to enable any person skilled in the art to practice the invention, the scope of which is indicated by the appended claims.

What I claim as my invention is:

1. A motor of the character described compris-

ing a pair of combustion chambers, an air inlet valve for each chamber adjacent one end thereof, fuel ignition means in each chamber, a restricted jet exhaust for each chamber connected to the opposite end thereof, means associated with each chamber directly responsive solely to increase of pressure in the other chamber to open its air inlet valve, and means associated with each chamber directly responsive solely to reduction of pressure in the other chamber to close its air inlet valve and actuate its fuel injection means.

2. A motor as defined in claim 1 in which the means for operating the air inlet valves and actuating the fuel injectors comprises a cylinder mounted adjacent each chamber, a conduit connecting each cylinder to the chamber remote therefrom, a piston in each cylinder, a lever connected to each piston, connections between each lever and the air inlet valve and fuel injection means of the adjacent chamber, and spring means urging said lever in one direction.

3. A motor as defined in claim 2 comprising means mounting said levers intermediate their ends adjacent said air inlet valves, first rigid members connecting one end of each of said levers to the adjacent piston, second rigid members connecting the other end of each of said levers to the adjacent air inlet valve, said valves being movable inwardly of said chambers in opening movement, and said spring means are compression springs surrounding said second rigid members and disposed to oppose opening movement of said valves.

4. A motor as defined in claim 2 in which said fuel injection means comprises plunger pumps, means connecting the plungers of said pumps to said levers, said last means including adjustable connection means on said levers to vary the stroke of said plungers.

5. A motor as defined in claim 2 comprising adjustable air control valves controlling the inflow of air past said inlet valves, and single control means for effecting correlated adjustments of the stroke of said plungers, and the air inlet opening determined by said air control valves.

6. A motor as defined in claim 1 in which said ignition means comprises constantly effective ignition elements within said chambers.

7. In a motor of the character described, a combustion chamber, a head on said chamber having a central valve stem opening, a plurality of air inlet passages surrounding said central opening, and a valve seat at its inner side, all of said passages terminating at the inner side of said head within said valve seat, a rotary air control valve mounted on the outer side of said head having a central opening and a plurality of ports surrounding the opening to selectively control the flow of air through said passages, and an inlet valve in said chamber cooperable with said valve seat, said inlet valve having an actuating stem extending outward through said valve stem opening.

8. Structure as defined in claim 7 comprising a fuel injector connected to said chamber, and means for sequentially operating said inlet valve and injector.

9. Structure as defined in claim 8, said injector including a reciprocable element, and means including a single manual control member for varying the stroke of said element and effecting a correlated rotary adjustment of said air control valve.

10. Structure as defined in claim 9 in which the means for sequentially operating said inlet valve

and injector comprises a lever, pivot means mounting said lever for rocking movement about an axis spaced from and perpendicular to said valve stem, means connecting said valve stem and lever, and adjustable means connecting said reciprocable element to said lever.

11. Structure as defined in claim 10, said adjustable means comprising a slideway on said lever, and a rigid member connected at one end to said reciprocable element and having means at its other end adjustable along said slideway to vary the stroke of said reciprocable element.

12. In a motor of the character described, a combustion chamber having a relatively large air inlet opening, a valve seat in said chamber surrounding said opening, an air inlet valve in said chamber cooperable with said seat, means mounting said valve for movement toward and away from said seat, an adjustable air control valve associated with said opening, an adjustable fuel injector opening into said chamber, single manual control means for effecting simultaneous adjustment of said air control valve and said fuel injector comprising a lever, a fixed support for said lever, actuating means connected to said lever for rocking said lever about the axis of said pivot support between fixed limiting positions, rigid means connecting said lever to said air inlet valve, said fuel injector including a reciprocable pumping element, a rigid member connecting said element to said lever, and an adjustable connection between said lever and said rigid member operable to shift the point of interconnection toward and away from the pivot axis of said fixed pivot support to vary the stroke of said pumping element.

13. In a motor of the character described, a combustion chamber having a relatively large air inlet opening, a valve seat in said chamber surrounding said opening, an air inlet valve in said chamber cooperable with said seat, means mounting said valve for movement toward and away from said seat, an adjustable air control valve associated with said opening, an adjustable fuel injector opening into said chamber, single manual control means for effecting simultaneous adjustment of said air control valve and said fuel injector comprising a lever, a fixed support for said lever, actuating means connected to said lever for rocking said lever about the axis of said pivot support between fixed limiting positions, rigid means connecting said lever to said air inlet valve, said fuel injector including a reciprocable pumping element, lost motion mechanism connecting said element to said lever to provide a delayed movement of said element in both directions with reference to rocking movement of said lever, an adjustable connection between said lever and said lost motion mechanism operable to shift the point of interconnection toward and away from the pivot axis of said fixed pivot support to vary the stroke of said pumping element.

14. In an internal combustion engine having a plurality of combustion chambers, each combustion chamber having a head provided with a central boss apertured to form a sleeve, a plurality of passages extending through said head and surrounding said sleeve, said head having a valve seat at its inner side, all of said passages terminating at the inner side of said head inwardly of said seat, an air inlet valve in said chamber movable toward and away from said seat and having a stem extending through said sleeve, a rotary air control valve on the outer surface of said head having a central opening in which said sleeve is received and a plurality of ports cooperable with

said passages to control the amount of air admitted to said chamber when said air inlet valve is open.

15. Structure as defined in claim 14 comprising in addition an actuating device responsive to pressure developed by combustion within another of said chambers, a rocker arm connected to said device for actuation thereby and operatively connected to said valve stem, fuel injection means comprising a reciprocating pumping element operatively connected to said rocker arm, a spring surrounding said valve stem and supported at one end by said head, the opposite end of said spring being operatively connected to said valve stem, said air inlet valve being moved to open position by said device against the action of said spring, said spring being effective to close said air inlet valve and to supply the power for actuating said pumping element on its injection stroke.

16. Structure as defined in claim 15 comprising manually operable means for adjusting the effective point of operative connection between said rocker arm and said pumping element toward and away from the axis of said rocker arm to vary the stroke of said element.

17. Structure as defined in claim 16 comprising means connecting said manually operable means and said air control valve to effect adjustment of said air control valve in accordance with changes in stroke of said reciprocating pumping element.

18. Structure as defined in claim 17 in which said engine comprises a fluid passage connecting said actuating device to the interior of another of said combustion chambers for actuation by pressures developed by combustion of a charge therein.

19. An internal combustion engine comprising a plurality of chambers, each chamber having an air inlet valve and a fuel injector, means responsive solely and directly to elevated pressure resulting from combustion of a charge in one of said chambers for opening the air inlet valve of another chamber, and means responsive to reduction of pressure in said one chamber for initiating closure of the air inlet valve and actuation of the fuel injector of said other chamber.

20. Structure as defined in claim 19, said last means comprising a spring operatively connected to each of said air inlet valves and the fuel injector of the associated chamber.

5 21. An internal combustion engine comprising a plurality of combustion chambers, each having an air inlet valve, fuel injector and spring mechanism associated therewith, said fuel injector comprising a pumping element movable in suction and pressure strokes, said spring mechanism operatively connected to the associated air valve and pumping element to urge said valve toward closed position and to move said pumping element 10 in its pressure stroke, pressure actuated means responsive to elevated pressure in one of said chambers for controlling charging of another of said chambers by opening its air valve and moving its pumping element on its suction stroke and thereby energizing its spring mechanism, said spring mechanism being operable upon reduction of pressure in said one chamber to close its associated air valve and move its associated pumping element on its pressure stroke.

20 22. An internal combustion engine comprising a pair of combustion chambers, each chamber having an air inlet valve and a fuel injector, means responsive solely and directly to elevated pressure resulting from combustion of a charge 25 in either of said chambers to open the air inlet valve of the other chamber, and means responsive to reduction of pressure in said first identified chamber for initiating closure of the air inlet valve and actuation of the fuel injector of said other chamber.

25 30 23. Structure as defined in claim 22 in which said last means comprises a spring operatively connected to the air inlet valve and the fuel injector of each of said chambers.
